C. C. DELACROIX,
FUEL OIL BURNER,
APPLICATION FILED DEC. 1, 1917.

1,261,494.

Patented Apr. 2, 1918.

Attorney

UNITED STATES PATENT OFFICE.

CHARLES C. DELACROIX, OF NEW ORLEANS, LOUISIANA.

FUEL-OIL BURNER.

1,261,494.

Specification of Letters Patent.

Patented Apr. 2, 1918.

Application filed December 1, 1917. Serial No. 204,868.

To all whom it may concern:

Be it known that I, CHARLES C. DELACROIX, a citizen of the United States, residing at New Orleans, in the county of Orleans and State of Louisiana, have invented certain new and useful Improvements in Fuel-Oil Burners, of which the following is a specification, reference being had to the accompanying drawings.

- 10 This invention relates to fuel oil burners and has for its primary object to provide an improved burner tip or nozzle particularly designed for use in connection with fuel oil burners for boilers, whereby a maximum 15 spread of flame from the jet orifice is produced so that the heat is equally transmitted to the fire sheet of the boiler, and the necessity for employing baffle plates for this purpose is eliminated.
- 20 It is another object of the invention to provide in a fuel oil burner, a burner tip having a jet opening or orifice through which the flame is ejected in a plurality of directions so that unequal expansion of the 25 fire sheets of the boiler which frequently causes leaks at the seams and rivets, is obviated.

It is still another object of the invention to provide a fuel oil burner wherein air and 30 steam is mixed with the oil in the burner tube and the oil broken up into finely comminuted particles, whereby its thorough combustion is assured.

With the above and other objects in view, 35 my invention consists in the novel features of construction, combination and arrangement of parts to be hereinafter more fully described, claimed and illustrated in the accompanying drawing, in which,

40 Figure 1 is a longitudinal section of an oil burner constructed in accordance with the preferred embodiment of my invention;

Fig. 2 is a section taken on the line 2—2 of Fig. 1; and

45 Fig. 3 is an end elevation of the burner tube.

Referring in detail to the drawing, 5 designates the body or head of the burner. This body may be mounted in any preferred 50 manner and may be of any desired proportions so that a multiplicity of the burner tubes may be applied thereto. The body 5 is formed with any desired number of the laterally projecting, tubular extensions 6 which 55 are reduced and exteriorly threaded at their ends, as indicated at 7. Upon this tubular

extension of the burner body, the interiorly threaded end 9 of the burner tube 8 is adapted to be detachably engaged.

10 designates a steam supply pipe, preferably made of sections threaded together, one of said sections having threaded engagement, as at 11, in the body 5. This steam supply pipe extends concentrically through the tubular extension 6 on the burner body 65 and into the burner tube 8. The pipe 10 is provided with a removable tip 12 having a tapering or pointed end 13 provided with a substantially semi-circular jet opening 14 which is obliquely disposed downwardly, as 70 clearly shown in Fig. 1, so as to direct the steam jet against the bottom portion of the surrounding burner tube 8.

The body 5 of the burner is also provided in its upper and lower portions with passages 15 and 16, respectively. An air pipe 17, connected to the body 5, is in communication with the passage 15, while an oil pipe 18, detachably connected to the body, is in communication with the passage 16. These 80 passages 15 and 16 open into the tubular extension 6 of the burner body upon opposite sides of the steam supply pipe 10.

The outer end of the burner tube 8 is also of tapered or conical form, as indicated at 19, 85 and is provided with the obliquely disposed, upwardly inclined jet opening or outlet 20 which is reversely disposed with respect to the steam jet orifice 14.

In the operation of the invention, it will 90 be understood that oil, air and steam are simultaneously supplied to the interior of the burner tube 8. It will be understood that if desired, the steam supply may be cut off and compressed air alone utilized for 95 the purpose of breaking up the oil. As the oil is admitted to the burner tube and passes around the highly heated steam pipe 10, the same partially vaporizes so that when broken up by steam or air, a more highly 100 combustible mixture is produced. The steam escaping from the orifice 8 in the tip section 12 of the pipe in a downward and also in lateral directions, causes a whirling motion in the body of oil. The vaporized oil 105 being ignited at the inclined jet opening or orifice 20 of the burner tube, is spread in a fan-shaped form and is ejected by the pressure of steam and air in the burner tube both forwardly and upwardly, as well as 110 laterally from opposite sides of the burner tube. Thus, the heat is equally distributed

against the fire sheet of the boiler and the expansion of the fire sheet will be equal throughout its area, thus eliminating liability of leakage at the seams and rivets of the fire sheet and also resulting in a maximum utilization of the heat units so that the boiler can be operated with a minimum expenditure of fuel. The device has been thoroughly tested in practical use and found 10 highly satisfactory, as it enables a low grade of oil to be employed as fuel, thus greatly reducing the operating cost of marine engines and the like.

From the above description, taken in connection with the accompanying drawing, the construction, manner of operation and several advantages of the invention will be clearly and fully understood. The several parts of my improved burner may be easily 20 and quickly assembled or disconnected when it is necessary to clean the passages in the burner head. In view of the extreme simplicity of the device, it is also obvious that the same can be manufactured at small cost.

25 While I have shown and described the preferred construction and arrangement of the several elements employed, it is to be understood that the device is susceptible of considerable modification therein and I, therefore, reserve the privilege of adopting 30 all such legitimate changes as may be fairly embodied within the spirit and scope of the invention as claimed.

Having thus fully described my invention, 35 what I desire to claim and secure by Letters Patent is:—

1. In a fuel oil burner, a burner tube having an obliquely disposed, upwardly 40 opening outlet orifice, a steam injecting pipe extending into the tube and having an obliquely disposed, downwardly opening orifice, and oil supply means connected to the burner tube.

2. In a fuel oil burner, a burner head, a 45 burner tube detachably connected thereto having a conical tip provided with an obliquely disposed, upwardly opening outlet orifice of elongated form extending upon opposite sides of said conical tip, a steam 50 supply pipe centrally disposed through the burner head and extending concentrically

into said tube and having a tip provided with an obliquely disposed, downwardly opening jet orifice, and means for supplying oil to said tube upon one side of the steam 55 pipe and means for supplying air to said tube from the opposite side of said pipe.

3. In a fuel oil burner, a burner head having a tubular extension, a burner tube detachably threaded upon said extension 60 having a conical tip provided with an elongated, obliquely inclined, upwardly opening jet orifice extending upon opposite sides of said conical tip, a steam supply pipe mounted in the burner head having a tip 65 projecting into the inner end of said burner tube and provided with a downwardly opening, obliquely inclined jet orifice extending upon opposite sides of the tip, and means for supplying oil to the burner tube upon 70 one side of the steam supply pipe and means for supplying air to said tube from the opposite side of said steam pipe.

4. In a fuel oil burner, a burner tube having an outlet orifice at one end, a steam injecting pipe extending longitudinally into the burner tube and also having an angularly disposed outlet orifice delivering the steam toward the side wall of the burner tube, and means for separately delivering 80 oil and compressed air longitudinally into the burner tube around the steam injecting pipe.

5. In a fuel oil burner, a burner tube having an outlet orifice at one end, a steam 85 injecting pipe extending longitudinally into said pipe and having an outlet orifice disposed substantially midway between the ends of the burner tube, said outlet orifice of the steam injecting pipe being disposed 90 at an oblique angle relative to the axis of the burner tube, and means for separately delivering oil and compressed air longitudinally into the burner tube around the steam injecting pipe.

95 In testimony whereof I hereunto affix my signature in the presence of two witnesses.

CHAS. C. DELACROIX.
